US00D574655S

(12) **United States Design Patent**
Perella et al.

(10) **Patent No.:** **US D574,655 S**
(45) **Date of Patent:** **** Aug. 12, 2008**

(54) **CASE FOR STORING RECORDING MEDIA,
SUCH AS CDS OR DVDS**

(75) Inventors: **Daniel V. Perella**, Hudson, OH (US);
Anthony J. Decarlo, Bay Village, OH (US); **Vincent J. Thomson**, Avon Lake, OH (US)

(73) Assignee: **Ideastream Consumer Products LLC**, Parma, OH (US)

(**) Term: **14 Years**

(21) Appl. No.: **29/249,076**

(22) Filed: **Sep. 19, 2006**

Related U.S. Application Data

(62) Division of application No. 29/187,785, filed on Aug. 8, 2003, now Pat. No. Des. 562,048.

(51) **LOC (8) Cl.** **06-02**

(52) **U.S. Cl.** **D6/634; D3/294**

CLAIM

The ornamental design for a case for storing recording media, such as CDs and DVDs, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a case for storing media such as CDs or DVDs, showing our new design;

FIG. 2 is a front elevation thereof;

FIG. 3 is a rear elevation thereof;

FIG. 4 is a left side view thereof, the right side being a mirror image; and,

FIG. 5 is a top plan view thereof.
